UNITED STATES PATENT OFFICE.

NATHAN JEWETT, OF TOLEDO, OHIO, ASSIGNOR TO HIMSELF, AND THE PLANO MANUFACTURING COMPANY, OF PLANO, ILLINOIS.

KNOT-TYING DEVICE FOR GRAIN-BINDERS.

SPECIFICATION forming part of Letters Patent No. 284,430, dated September 4, 1883.

Application filed February 8, 1883. (No model.)

To all whom it may concern:

Be it known that I, NATHAN JEWETT, of Toledo, in the county of Lucas and State of Ohio, have invented certain Improvements in 5 Knot-Tying Devices for Grain-Binding Machines, of which the following is a specification.

This invention relates to that class of cord-tying devices which consist of a spindle provided with two laterally-extending bills or fingers, one movable and the other stationary, by which the cord is first twisted into a loop, and its end subsequently caught between the fingers and drawn through said loop to complete the knot.

My invention consists in a peculiar conformation and arrangement of the movable finger, which is mounted in a slot in the rigid finger and arranged to protrude on both sides 20 of the same, in such manner that the cord, acting upon the outer side, will serve to open said finger, which will be subsequently closed by the action of the cord upon its inner side.

Referring to the accompanying drawings, 25 Figure 1 represents a perspective view of my tyer-head, the movable finger being in its open position. Fig. 2 is a longitudinal vertical section through the tyer-head, the finger being in its closed position. Fig. 3 is a view 30 of the tyer, looking against the end of the fingers, as indicated by the arrow in Fig. 2. Fig. 4 is a perspective view, illustrating the manner in which the finger is opened by the action of the cord on the outside.

35 A represents a revolving shaft or spindle. B represents the stationary tying-finger at one end of the spindle, and C the movable tying-finger. The finger B, at its inner or heel end, is made of considerable size, with a spiral 40 or tapering outer surface, to assist in forcing the cord to its outer end, substantially as in other tyers of this class. From its inner enlarged end the finger tapers or diminishes in size toward its extremity, which is extended 45 in a line at right angles, or substantially so, to the axis of the spindle A. Through the stationary finger B, in line with the axis of the spindle, I form a slot or mortise of sufficient size to receive the movable finger C, which is 50 secured therein by a pivot-pin, a, upon which

the finger is free to rock to a limited extent. The outer end of this movable finger lies within or opposite the inner face of the stationary finger B, upon which it may be closed, and is tapered to a point. On its outer face this 55 point is provided with a notch or shoulder, e, designed to receive and retain the cord when the end of the finger is closed against the stationary finger, as shown in Fig. 2. At its rear or heel end the movable finger is provided with a rounded projection, d, which extends beyond the outer surface of the stationary finger whenever the movable finger is in its open position—that is to say, with its outer end thrown away from the stationary finger. 60 The rocking motion of the movable finger upon its pivot is limited in one direction by the contact of the two fingers at their outer ends, and in the opposite direction by a shoulder, e, encountering the end of the slot in the 65 spindle.

In making use of my tyer-head it will be mounted in a machine of any approved form provided with means for imparting a rotary motion to the spindle, and with devices for 75 presenting the cord in proper position across the tyer-head and retaining the ends. Various arrangements of this kind suitable for use in connection with my device being well known in the art, it is deemed unnecessary to describe 80 them in detail herein.

The operation of the device is as follows: The ends of the cord forming the applied band being laid across the head inside of or behind both fingers, the head is revolved. The first 85 effect of this rotary motion is to cause the cord to be wound into the form of a loop, in substantially the same manner as in other analogous devices. As the formation of this loop is completed the cord acting upon the rear 90 projecting end, d, of the movable finger serves to press said finger inward, causing its outer or forward end to separate from the stationary finger, thereby leaving an open space between them for the admission of the end of the cord, 95 which is thus brought between them by their continued rotation. After the end of the cord has been laid between the fingers the rotation of the head permits the loop to slide forward over the fingers toward their end, thus reliev- 100

ing the shoulder *d*, and permitting the end of the movable finger to be drawn inward by the action of the loop toward and against the stationary finger to the position represented in Fig. 2, whereby the end of the cord is retained firmly between the two fingers, so as to be drawn thereby through the loop as the latter is carried off over the fingers, in the manner well understood by those familiar with the subject.

I am aware that tyers of various forms have been provided with movable fingers operated by means of the cord, and this I do not claim; but I believe myself to be the first to construct 15 a tyer combining a stationary finger and a movable finger, the operative end of which acts against the inner face of the stationary finger, while its heel end is projected through and beyond the stationary finger, so as to be 20 acted upon by the cord upon the outer side to effect the opening of the finger.

It is obvious that the form of the parts may be modified within reasonable limits without departing from the limits of my invention, 25 provided the movable finger is adapted, substantially as described, to be opened by the action of the cord on the outer side and closed by the action of the cord on the inner side.

It is preferred to construct the end of the 30 finger *B* with a longitudinal groove or slot in its inner face to receive the end of the finger *C*, the better to secure the cord between the two ends; but this is not a necessary feature of the device. It will be observed that the inner rear 35 edge of the movable finger has an inward curva-

ture or indentation, *f*. When the finger is in its open position, this curved edge co-operates with the inner edge of the stationary hook, and serves to keep the cord in position near the center of the head during the formation 40 of the loop, avoiding the excessive use of cord, and keeping the same in such position that it will be certain to act upon the shoulder *d* to hold the finger open during the proper period of time.

I do not claim herein any device or combination of devices represented in my application for Letters Patent filed February 7, 1883, No. 84,253.

Having thus described my invention, what 50 I claim is—

1. In a cord-tyer, the combination, with the rigid finger *B*, of the movable finger *C*, having one end arranged to act against the inner side of the rigid finger, and its opposite end 55 projected beyond the opposite side of said rigid finger.

2. In combination with the revolving finger *B*, lying at substantially right angles to its axis of rotation, a pivoted tying-finger extending 60 through said revolving finger and projecting on both sides thereof, substantially as described, adapted to be moved in opposite directions by the action of the cord upon its respective ends or sides.

NATHAN JEWETT.
